UNITED STATES PATENT OFFICE.

EUGENE SCHIMPFF, OF SCRANTON, PENNSYLVANIA.

SECTIONAL BOAT.

Application filed January 30, 1922. Serial No. 532,541.

To all whom it may concern:

Be it known that I, EUGENE SCHIMPFF, a citizen of the United States, residing at Scranton, in the county of Lackawanna and State of Pennsylvania, have invented certain new and useful Improvements in Sectional Boats, of which the following is a specification.

This invention relates to collapsible or "knock-down" boats which can be conveniently reduced in size for the purposes of shipping, storing, etc.

It is one object of this invention to provide not only for a readily collapsible boat, but also one which may be set up with comparatively little effort to provide a boat which is free from vibrations and of much strength and safety.

Other objects and advantages will hereinafter appear.

In the accompanying drawings:

Fig. 1 is a plan view of the boat forming the subject of this invention.

Fig. 2 is a vertical, longitudinal section of the boat as shown in Fig. 1.

Fig. 3 is a bottom view of the boat as shown in Fig. 1.

Fig. 4 is a plan view showing the boat in collapsed position ready for shipping or storing.

Fig. 5 is an end view of one of the boat sections showing the method of attaching the connecting members.

Fig. 6 is a perspective view of the lower part of the connecting member.

Fig. 7 is a perspective view of the upper part of the connecting member.

Referring to the drawings, there is shown a boat comprising a middle section 10, a rear or stern section 11, and a front or bow section 12. Each section is a floating vessel in itself, being water-tight, and it is therefore possible to leave spaces 15 and 16 between adjacent boat sections to form water-tanks in which fish or bait may be carried. The relative sizes of the boat sections are such that the stern section may fit inside of the middle section, and the bow section may fit inside the stern section to form a nest of sections (see Fig. 4). In order that rib 17 forming one side of tank 15 may fit around rib 18, said rib 17 is made slightly larger than rib 18. Rib 19 forming one side of tank 16 is in turn slightly larger than rib 17. The entire boat may thus be enclosed in a space no greater than

that occupied by the middle section alone. The desirability of this feature for the purposes of packing, shipping, or storing will be obvious. While the end sections have been described as fitting into the middle section, it will be understood that any section of the boat may be made of a size sufficient to accommodate the other sections, the same principles applying. It will also be understood that the invention is not limited to a boat comprising three sections, but is applicable also to a boat comprising any suitable number of sections.

In setting up the boat from the Fig. 4 or collapsed position, the rear rib 19 of the bow section is brought against the front rib 20 of the middle section, and the front rib 17 of the stern section is brought adjacent the rear rib 18 of the middle section. Between adjacent ribs at each side of the boat there is formed a V-shaped cavity 22 in which is inserted a connecting member having a wedge-shaped stem 25 which fits snugly in said cavity and horizontal flanges 26 which support the adjacent boat sections. Projections 27 fixed to said flanges and projecting upwardly into openings 28 in the boat sections hold said sections at the bottom against movement laterally relative to each other. The sections are held against movement at the top by members 29 having spaced prongs or projections 30, the upper edges of adjacent ribs fitting into the space between said prongs, the latter thus preventing spreading of the boat sections at the top. Each member 29 has an opening 31 through which passes freely the upper screw-threaded end of stem 25. A nut 32 screwed upon said stem thus clamps all parts of the connecting member in position upon the boat sections. The sections are thus held at the top and bottom against lateral movement away from each other by the members 29 and the projections 27 in openings 28, respectively, and are held against vertical movement relatively to each other, since the sections are clamped tightly between member 29 which acts as an upper flange and the lower flanges 26. In the boat shown in the drawings there are four connecting members since there are two joints, but any number of sections may be similarly united, it being understood that a connecting member is provided at each joint and at each side of the boat.

While the connecting members at the

joints are sufficient to hold the boat sections together, additional security may be obtained by hinged connections between adjacent sections positioned on the bottom of said sections. Each of said connections comprises a hinge 40 carried by one of the sections and engageable with the adjacent section as by a ring 41 passing through the hinge and a suitable fastening member such as a bolt 42 passed through said ring. Any other suitable clamping or locking device may also be employed.

The above description represents a preferred embodiment of my invention, but variations may be resorted to within the scope of the annexed claims.

Claims:

1. A sectional boat comprising a middle section, a bow section, and a stern section, 20 said sections being detachable, each of said sections being a floatable body, ribs formed by the abutting edges of each section, said ribs having an offset portion to provide water-spaces between said bow section and said middle section and between said middle section and said stern section.

2. A sectional boat comprising a plurality of detachable sections, and clamp connecting members having stem portions arranged at each side of the boat and end members on said stems engaging top and bottom edges of adjacent sections to fasten said sections together.

3. A sectional boat comprising a middle section, a bow section, and a stern section, 35 said sections being detachable, clamp connecting members having a stem portion arranged at the sides of the boat and end members on said stem engaging top and bottom edges of adjacent sections for fastening said sections together.

4. A sectional boat comprising a plurality of detachable nesting sections, connecting members at the adjacent side walls of 45 each section of the boat engaging the side walls and top and bottom edges of adjacent sections for fastening the sections together, and hinged fastening members beneath said sections for fastening adjacent sections together.

5. A sectional boat comprising a middle section, a bow section, and a stern section, 55 said sections being detachable, and clamp connecting members having a stem portion arranged at the sides of the boat and having end members for engaging the top and bottom edges of adjacent sections for fastening said sections together to prevent vertical or lateral movement of said sections relative 60 to each other.

6. A sectional boat comprising a middle section, a bow section, and a stern section, 65 said sections being detachable, and connecting members having a stem portion arranged at the sides of the boat and having

end members on the stem for engaging the top and bottom edges of adjacent sections for fastening said sections together.

7. A sectional boat comprising a middle section, a bow section, and a stern section, 70 said sections being detachable, and connecting members for fastening said sections together, said members comprising means engaging adjacent sections at the bottom to prevent lateral movement and means engaging adjacent sections at the top and bottom and adjacent walls of adjacent sections to prevent vertical movement of the sections relative to each other.

8. A sectional boat comprising a middle section, a bow section, and a stern section, 80 said sections being detachable, and connecting members for fastening said sections together, said members having projections at one end cooperating with adjacent sections, 85 said sections having openings for receiving said projections, said members having projections at the other end for engaging adjacent sections, said projections preventing lateral movement of said sections relative to 90 each other.

9. A sectional boat comprising a middle section, a bow section, and a stern section, 95 said sections being detachable, and connecting members for fastening said sections together, said members having a flange at one end, projections on said flange cooperating with adjacent sections, said sections having 100 openings for receiving said projections, said members having a flange at the other end, said last-named flange having projections for engaging adjacent sections, said projections preventing lateral movement of said sections relative to each other, and means for moving 105 said flanges toward each other to clamp adjacent sections against vertical movement 110 relative to each other.

10. A sectional boat comprising a middle section, a bow section, and a stern section, 110 said sections being detachable, and connecting members for fastening said sections together, said members each comprising a stem extending upwardly between adjacent sections, flanges at the lower end of said stem, 115 said flanges having projections thereon for cooperation with adjacent sections, said sections having openings in the bottom for receiving said projections, a flanged member on the upper end of said stem and having a projection for engaging the top of adjacent sections, the upper end of said stem being threaded, and a nut on said threaded end for moving said top and bottom flanges toward each other to clamp said sections against vertical movement relative 120 to each other.

11. A sectional boat comprising a plurality of sections, V-shaped recesses at the sides of said boat between adjacent sections, and wedge-shaped connecting members fitting 125

into said recesses for fastening adjacent sections together and preventing vibration of said sections.

12. A sectional boat comprising a middle section, a bow section, and a stern section, said sections being detachable, each of said sections having adjacent upwardly extending bowed rib end walls forming compart-

ments between the sections and means for fastening the sections together. ¹⁰

In testimony whereof I affix my signature in presence of two witnesses.
